UNITED STATES PATENT OFFICE.

FRANK L. SESSIONS, OF COLUMBUS, OHIO, ASSIGNOR, BY MESNE ASSIGNMENTS, TO THE JEFFREY MANUFACTURING COMPANY, A CORPORATION OF OHIO.

CIRCUIT-BREAKER.

1,072,178.

Specification of Letters Patent.

Patented Sept. 2, 1913.

Application filed October 9, 1905. Serial No. 282,047.

To all whom it may concern:

Be it known that I, FRANK L. SESSIONS, a citizen of the United States, residing at Columbus, in the county of Franklin and State of Ohio, have invented certain new and useful Improvements in Circuit-Breakers, of which the following is a specification, reference being had therein to the accompanying drawings.

10 This invention relates to improvements in circuit breakers, the devices by which electric circuits are opened and closed as desired.

15 The object is to provide a circuit breaker which will be capable of opening circuits which carry powerful currents, without disastrous results from the arcs which are formed.

20 Figure 1 is a front view of a circuit breaking device embodying my improvements. Fig. 2 is a horizontal section on the line 2—2 of Fig. 1. Fig. 3 is a central transverse vertical section on the line 3—3 of Fig. 2. Fig. 4 is a vertical section taken on the line 25 4—4 of Fig. 3. Fig. 5 is a vertical section taken on the line 5—5 of Fig. 3. Fig. 6 is a diagrammatic view showing the path of the current across the brushes and around the magnet coil, and also showing the path 30 taken by the arc when it is blown out by the lines of force of the magnet.

35 Among the objects of the invention are these, namely, to provide a cylindrical switch which can operate accurately in relation to the terminal brushes; to insure that this switch shall have its contact surfaces maintained smooth and not affected by the flame or heat of the arc; to provide means for accurately adjusting the magnetic tripping devices so that the breaker can be "set" 40 for any predetermined strength of current, within limits, and to provide a visual indicator to indicate at any time the strength of current requisite to automatically operate 45 the circuit breaker.

A casing is provided to support and cover the operative parts of the device, it having a back part K and a front part K'. These are, each of them, box-like in conformation. 50 Their open sides are adapted to be fitted together, edge to edge, the plane of contact being shown at k'. They are firmly fastened together by means of the screws or bolts k. A part of the lower side of each of these sections of the casing is cut away so as to form

a slot or passage as shown at K^s to permit the movement of the lever of the circuit breaker. The rear part K of the casing is made of diamagnetic material, such as zinc. The front part K' of the box or casing may 60 be made of similar material, though it is not of as much importance, and may be of iron. In the front wall of the front part K' of the casing is a slot K^g for a purpose to be described. At a, a', there are apertures 65 in the side walls for the introduction of the terminal wires of the circuit.

The rear part K of the box or casing is secured to a suitable support as at M by means of screws such as shown at k², k⁴. This part 70 K supports the metallic part F', which constitutes one of the pole pieces of the magnet to be more fully described, there being screws or bolts as at f⁴, f⁶, f⁸ for fastening it to the back wall of the rear part K of the box. 75

F² is a core piece which is secured in a threaded aperture in the pole piece or plate F'. At its front end core piece F² has a flange or expanded head F³ in the lower part of which there is formed a transverse pivot 80 aperture. F represents the second pole piece of the magnet. It is pivotally connected to the core F² by means of the pivot pin f² passing through the aforesaid aperture in the bottom of the flange F³, and 85 through ears f⁷ on the hinge piece F. The magnetic circuit will now be understood to be from the core piece F² to the pole piece F, thence across to the pole piece F' and back to the core. 90

The coil of the magnet is indicated at H². The lines of force of this magnet are utilized for blowing out the arc which tends to form between the brushes of the stationary terminals of the circuit and which I will now 95 describe.

A indicates one of the brushes, A' the other.

B is the rotary switch piece which is adapted to be turned around an axis in such 100 way as to electrically connect the brushes A and A' by contacting with both of them. As shown, it consists of a segment of a ring of metal. It is rigidly secured to a handle device indicated as a whole by C. This 105 comprises the insulating handle C' which projects below the casing and is adapted to be grasped by hand; also a pivoted yoke having the legs C², C³; and also the binding or clamping bolt C⁴. The switch piece 110

B is insulated from the handle C' and from the legs C², C³ of the fork by means of the insulated washers c, c' and the bushing c². The binding bolt C⁴ extends lengthwise through the handle C', and has its head C⁵ seated in a cavity in the outer end of the handle, which cavity is closed by the insulating piece C⁶. These parts, to-wit, the handle, the switch segment B and the fork C², C³ are hinged to the core piece F², the leg C² of the fork being secured by the pivot f³, and the leg C³ by the pivot f⁸. The latter pivot passes through the aperture f⁹ in the movable pole piece F.

15 It will be observed that the core F² sets out or away from the casing walls; and that the arms C², C³ of the handle, while within the casing, are pivoted to the ends of the core piece outside of or beyond the planes of the coil H², thus making a very simple and compact arrangement of parts, and one that is easily accessible upon the opening of the casing.

20 It will be seen that by grasping the handle C' the switch segment B can be turned around its axis in such way as to move into and out of contact with the brushes A, A'. A spring D tends to normally turn the handle and the switch segment to the "off" position, this spring being secured to the casing at d', and to an extension E on the leg C² of the fork. This extension has a shoulder at e² serving as one element of a catch, the other element being a latch dog E', which is pivoted to the casing at e'. When the handle C is thrown in such way as to bring the switch segment to the "on" position, the latch E' drops into position in front of the shoulder e², and the spring D, though under tension, is prevented from opening the switch.

25 When the current passing through the circuit exceeds a predetermined quantity the circuit breaker is automatically opened, as follows: The swinging pole piece F is normally held in its outermost position by a spring G, which is riveted at g to the casing wall, and at its upper end fits loosely under the pin G' on the pole piece. The 30 tension of the spring G is adjusted for the desired amount of current. When this is exceeded there is an increase in the energizing of the magnet F, F', F², and the swinging pole F overcomes the tension of the spring G and moves toward the opposite pole F'. This motion is utilized to move the latch E' so that the spring D will be free to move the switch ring B and break the circuit. The pole piece F is formed 35 with an arm f which extends outward from the line of the axis at f², and the end of this arm lies under a vertical sliding pin or rod f' which is mounted in guides e³ on the casing wall. The upper end of this rod f' lies immediately under a lug e

40 on the latch bar E'. When the pole piece F swings inward its arm f' lifts the latch piece E' and releases the fork lever so that the spring D can instantly draw the switch segment B away from the brush A' and open the circuit. When this separating of the part B from the part A' occurs, an arc is formed between the parts A, A'. Under the action of the lines of force of the magnet this arc is compelled to travel, or is 45 "blown," outward as indicated by dotted lines in Fig. 6. Each of the brushes A and A' has two active surfaces, one at a² and the other at a³. The surface at a² acts in conjunction with the switch part B, and the surface at a³ acts to carry the arc. The surfaces a³, a³, it will be seen, diverge from each other, and consequently the arc is rapidly elongated and very quickly dissipated. By having the arc located between 50 these surfaces a³, a³, the surfaces a² are saved from burning. These parts, namely, the switch segment B, and the brushes A, A' are all mounted in an insulated chamber or chimney. It is formed by the rear 55 insulating wall K², the front wall K⁴ and the side walls K⁵, K⁶; and at K⁷ insulation is interposed between the core F² and the coil H². The pole pieces F and F' are situated outside of this insulating chamber. It is open at the top as shown at 60. The heated air and gases can readily escape to the atmosphere, the direction taken by the arc in approaching this open top being shown in Fig. 6, where the dotted lines at 65 K⁵, K⁶ indicate, approximately, the positions of the insulating walls.

70 P indicates the terminal portion of the conductor over which the current may be regarded as traveling in its approach toward the circuit breaker, and P' indicates the terminal part of the conductor for the current as it leaves the device.

H indicates a binding post for the in-lead P, and H³ a binding post for the out-lead.

75 The brushes A, A' are yieldingly mounted upon spring arms or plates A⁴, A⁵. The lower end of the arm A⁴ is secured to an extension h' of the binding post H, and the arm A⁵ is secured to an extension h² of a binding post or terminal holder H'. The current entering along the conductor P passes over the arm A⁴ to the brush A, and thence through the switch segment B, when the latter is in the position shown in Fig. 80 5, to the brush A', thence along the arm A⁵ to the binding post H'. From this it travels to the coil H² over the terminal h³, and from the coil along the terminal h⁴ to the binding post H³, whence it passes out on 85 the conductor P'.

90 The binding posts H' and H³ are firmly secured to the insulating plate K². The path of the current is indicated by the arrows in Fig. 6.

The spring G which normally holds the hinged pole piece F in its outermost position can have its tension varied as required. One way of accomplishing this is illustrated in the drawings. At points above the fastening device g the spring has a slot g'. Through this is passed a screw G², the head g² lying inside of the spring G. The shank of the screw passes through the slot K⁹ in the face plate of the casing section K'. The outer threaded end of the screw G² is provided with a clamping nut g³. If this be loosened the screw G² can be moved up or down in the slots K⁹ and g'. If it be adjusted to relatively higher points it will require greater force to bend the spring G inward, and vice versa.

g⁴ is a bushing having flat sides fitted to the sides of the slot K⁹, so that it can be moved vertically, but cannot be rotated. It has a flange bearing against the outer face of the cover, and from this flange projects a pin g⁵. The nut g³ has several notches g⁶, each adapted to engage with the pin g⁵. When sufficient effort is exerted upon the nut it can be turned, but not until the spring G has been forced outward far enough to permit the nut to leave the surface of the flange g⁴, and pass over the pin g⁵.

At G³ there are graduations along the slot K⁹, these indicating the quantity of current required to trip the circuit breaker with the different adjustments of the screw G². The flange g⁴ is provided with an index projection g⁷ to indicate accurately the position of the adjusting screw.

It is sometimes necessary to manually open the latch E' and release the switch lever so that the spring D can act upon it. This is done by means of a push pin L mounted in the front part of the casing and adapted to engage with the upper end of the swinging pole piece F. By pushing in upon this pin L the pole piece F is moved to its inner position, and in doing so its trip arm f thrusts the pin f' upward, which, in turn, lifts the latch E' in the way above described.

By examining Fig. 5 it will be seen that the switch segment B, when in the "on" position, has an end part b which projects considerably beyond the contact surface a² of the brush A'. The purpose of this extension to the switch segment is that it shall carry the arc when the circuit is broken or opened, that is, when the switch segment B is escaping and moving away from the brush A'; whatever burning of the metal of the movable segment takes place will be experienced by this projecting part b, and the contact portions of the outer surface of the segment will not be roughened by the burning action, but will remain smooth, so as to have smooth contact with the brushes over the whole contact surface.

What I claim is:

1. In a circuit breaker, the combination of the supporting device, the magnet pole piece secured to the supporting device, the magnet core, the movable pole piece supported on the core, the insulating chamber between the pole pieces, the magnet coil in the insulating chamber, the terminal brushes in the insulating chamber, and the rotary switch segment, substantially as set forth. 70

2. In a circuit breaker, the combination of the magnet pole piece, the stationary support therefor, the magnet core, the movable pole piece for the magnet, the terminal brushes, the rotary switch segment between the brushes, and the rocking support for the said switch segment pivoted to the ends of the magnet core, substantially as set forth. 75

3. In a circuit breaker, the combination of the magnet pole piece, the stationary support therefor, the magnet core, the movable pole piece, the terminal brushes between the pole pieces, the rotary switch segment engaging with the brushes, and the yoke-like carrier for the switch segment, the legs of said yoke being pivotally supported on the longitudinal lines of the magnet core, substantially as set forth. 80

4. In a circuit breaker, the combination of stationary terminal brushes of an electric circuit, an oscillatory switch piece between said brushes, a magnet core having its axis parallel to the axis of oscillation of the switch piece, opposite magnet pole pieces arranged adjacent to and on opposite sides of the said brushes, whereby the lines of magnetic force passing between the pole pieces will operate to blow out an arc that may form between the brushes, one of the said pole pieces being movable toward or from the other, means for providing an electric circuit around the core, means for breaking such circuit, and a lock for circuit breaking means arranged to be released by the said movable pole piece, substantially as set forth. 95

5. In a circuit breaker, the combination of terminal brushes, a rotatable switch segment arranged to make connection between the brushes and a stationary magnet for blowing out the arcs between the brushes, the said magnet having two pole pieces, a stationary core and a coil surrounding the core, the said core, coil, switch segment and the contact faces of the brushes being arranged in concentric relation to each other and being situated in the same transverse plane, substantially as set forth. 105

6. In a circuit breaker, the combination of the magnet coil, a core within the said coil, a pole piece fixed with respect to the core, a second pole piece movable with respect to the core, a switch segment rotating around the axis of the magnet coil in the single air gap between the pole faces of the said pole pieces, terminal brushes also mounted in the 115

single air gap between the pole faces of the said pole pieces, the movable pole being adapted, as it diminishes the air gap, within which the said switch segment and brushes are mounted, to permit the action of the switch moving mechanism.

7. In a circuit breaker, the combination of the chamber formed of insulating walls, the magnet core arranged across the said chamber, the magnet poles on the outside of the said walls, the rotary switch segment, the terminal brushes mounted on yielding supports, and the magnet coil, said switch segment, brushes and magnet coil being all located within the said insulating chamber, substantially as set forth.

8. In a circuit breaker, the combination of the chamber having insulating walls, the magnet core extending across said chamber, the magnet coil, the rotary switch segment, the terminal brushes, the said coil, switch and brushes being arranged concentrically within the said insulating chamber, the magnet pole pieces outside of the insulating chamber, and the support for the switch segment situated outside of the said chamber and mounted to rotate on the axis of the magnet core, substantially as set forth.

9. In a circuit breaker, the chamber having insulating walls, the magnet core extending across said chamber, the magnet coil, the rotary switch segment and the terminal brushes all being within the said chamber, the stationary pole piece secured to the core and arranged to support the aforesaid parts, and the movable pole piece opposite to the stationary pole piece, substantially as set forth.

10. In a circuit breaker, the combination of the chamber having insulating walls, the magnet core extending across the chamber, the magnet coil, the rotary switch segment, and the terminal brushes all situated within the said chamber, the movable pole piece mounted on the core, and the stationary pole piece arranged to support all of the aforesaid parts, substantially as set forth.

11. In a circuit breaker, the combination with the brush terminals of the circuit, of the movable switch piece B, the supporting yoke C², C³, the handle C', means for binding together the switch piece, the yoke and the handle, and means for insulating the switch piece from the yoke and the handle, substantially as set forth.

12. In a circuit breaker, the combination of the chamber having the insulating walls K², K⁴, the magnet having the core F² passing through the insulating chamber, the pole piece F' rigidly secured to the core, and se-

cured to a stationary support, the hinged pole piece F, the pole pieces F and F' being outside of and adjacent to the insulating walls K², K⁴, the magnet coil the brush terminals A, A' and the switch segment B all between the insulating walls, means for automatically moving the segment B around the axis of the core F², a lock for the last said means, and the trip device for the lock actuated by the pole piece F, substantially as set forth.

13. In a circuit breaker, the two-part box or casing, the insulating chamber, the circuit terminals and the rotary switch segment within the insulating chamber, the magnet having its pole pieces arranged within the casing, all supported on the inner section of the casing, and the outer section being separable from the inner, in the plane of the insulating chamber, substantially as set forth.

14. In a circuit breaker, the combination with the insulating chamber, the magnet coil, the terminal brushes, and the rotary switch segment, all within the insulating chamber, of the two magnet pole pieces outside of the insulating chamber, and the two-part casing inclosing the said insulating chamber and pole pieces, one part of said casing being formed of diamagnetic material, substantially as set forth.

15. In a circuit breaker, the combination of the insulating chamber, the magnet coil, the terminal brushes, and the rotary switch segment, all within the insulating chamber, of the pole pieces outside of the insulating chamber, and the two-part casing, the inner part of which supports all of the aforesaid devices, substantially as set forth.

16. In a circuit breaker, the combination with a magnet core and two pole pieces, one rigid with respect to the core and the other pivotally mounted thereon, of terminal brushes and the rotary switch segment mounted in the single air gap between the pole faces of the said pole pieces.

17. In a circuit breaker, a blowout-magnet having a core and a pole piece fixed with respect to the core, and a second pole piece movably mounted on the core and electric contact devices mounted in the single air gap between the pole faces of the said pole pieces.

In testimony whereof I affix my signature, in presence of two witnesses.

FRANK L. SESSIONS.
